Primary Examiner—Raphael H. Schwartz
Attorney—Pearson and Pearson

ABSTRACT: A container such as a potato bag, of the type normally closed by bunching the neck and twisting a wire tie, into a loop around the neck is provided with a hand grip attached to the looped tie. The closed bag may thus be lifted by the hand grip rather than by the bunched neck. The pull on the handle snubs the wire tie into a firmer grip on the neck of the bag.

COMBINED WIRE BAG TIE AND HANDLE

BACKGROUND OF THE INVENTION

A wire tie closure for potato bags is well known. One who has sought to carry a potato bag from market to car, or car to house, by gripping the elusive and slippery material of the bunched neck, will be aware that this is not an efficient handle.

It has heretofore been proposed to provide a potato bag with a built in wire tie, as in U.S. Pat. No. 2,980,314 to Adams of Apr. 18, 1961, and it has been proposed to use a tape as a bag tie and form a loop in the tape as a handle in U.S. Pat. No. 2,849,171 to O'Brien of Aug. 26, 1958. Forming the tie into a handle loop is also taught in U.S. Pat. No. 3,066,846 to Domigan of Dec. 4, 1962.

It will be understood that using a wire, or tape, narrow enough to be successfully tied, or twisted, as a carrying handle, by joining the terminal ends into a loop, will create an uncomfortable, small cross section loop which will cut into the hands when the bag is a heavy potato bag.

SUMMARY OF THE INVENTION

In this invention, therefore, the bag closing tying means is of bendable wire, and the handle means is of some material other than wire, such as sheet, or molded plastic, and the metal tie is received in an opening in the handle means. The handle means is substantially flat and relatively wide in the upper portion to include a finger aperture and offer a comfortable grip to the user. The lower portion is flexible and tough, and tapers to a reduced width substantially conforming to the dimensions of the bunched neck of the bag. The lower portion is turned back upon itself to form an opening, or loop, which receives the central portion of the wire tie. The hand grip thus can normally lie down against the bag, but, when grasped and lifted, it tilts the wire tie loop to cause a snubbing action, or may even cause the wire to embed itself in the folds of paper, thereby assuring that the loop will not slip off the neck.

BRIEF DESCRIPTION OF THE DRAWING

FIG. 1 is a fragmentary perspective view showing a device of the invention with the hand grip not in use;

FIG. 2 is a view similar to FIG. 1, showing the hand grip in use and the loop tilted;

FIG. 3 is a side elevation, on an enlarged scale;

FIG. 4 is an end elevation, of a device of the invention prior to use;

FIG. 5 is a fragmentary view, similar to FIG. 3 of another embodiment of the invention; and

FIG. 6 is a view similar to FIG. 4 of another embodiment of the invention.

DESCRIPTION OF PREFERRED EMBODIMENT

As shown in drawing, the combined bag closer and carrying handle 20 of the invention is intended for use on a container such as the potato bag 21, such bags usually being made of heavy paper 22. At present it is the custom to close and seal the filled bag 21 by bunching the mouth portion 23 into a neck 24, the neck usually being rather short to conserve paper. A tying means 26 is provided, consisting of an elongated flexible, or easily bendable wire, or equivalent wirelike element, 27, having terminal loops 28 and 29, and adapted to be encircled in a loop 30 around neck 24 with the end portions 31 and 32 twisted, all in a known manner.

The member 20 also includes the handle means 35 having a substantially flat hand grip 36, molded or otherwise formed from material other than wire, such as synthetic plastic or equivalent disposable, low cost sheet, or moldable, material 37. The upper portion 38 of the hand grip 36 is relatively wide to conform comfortably to the dimensions of an adult hand, and includes a finger aperture 39 defined by the transverse bar 40 and the lower portion 41, which tapers to a reduced width at 42. The upper portion 38 may be somewhat rigid and of increased thickness for comfort in use, while the lower portion

41 may be integral but more flexible, limp and tough to avoid breakage, or tearing. The terminal tip 42 of lower portion 41 is turned back upon itself, and adhered by staples, adhesive or heat sealing of the plastic to create an opening, or loop, 43, which receives the central portion 44 of the wire tie 27.

The tip 42 is about the same width as the diameter of the neck 24 so as to conform with its dimensions.

In FIG. 5 an embodiment is shown in which the tying means 26 is a relatively short, stiff wire 47, received in openings 48 and 49 in the tip 42. Instead of manual bending and twisting of the tie, the wire 47 is adapted to be bent into clamping engagement around neck 24 by a tool, such as pliers, staplers, or clamping devices.

In operation, the members 20 of the invention are attached 15 to the potato bags, after filling thereof, and form collapsed handles ready for use by the consumer. When the handle 35 is lifted and the heavy bag raised, the bag pulls in one direction and the hand grip in the opposite direction, so that the wire loop cannot slip, but is tilted into a snubbed position. Upon 20 release, however, the handle grip may assist in removing the wire loop, although it is preferred that the loops be applied tightly and require untwisting for removal.

In FIG. 6 another embodiment is shown, in which the tip 42 is of increased thickness to form a bead 50, about one-fourth 25 inch in thickness. The handle means 35 is attached to the tying means 26, when the wire loops 28 and 29 are bent together, by slipping the bead 50 under the loop 30. The tightness of the parts prevents the bead from slipping out.

It will be seen that in the embodiments of FIGS. 1-5 annular means such as the openings 48 and 49, or the opening formed by closed loop 43 serves to prevent disengagement of the handle from the tie during use as a handle on the bag, or thereafter. When the tie is separated from the bag, by unfastening or sliding, it remains attached to the handle except in the embodiment of FIG. 6.

I claim:

1. In a combined bag closer and carrying handle for use with relatively heavy potato bags, the combination of:
a substantially flat handle having a relatively wide upper portion with a finger aperture adapted to serve as a hand grip, and a relatively narrow, integral, lower portion dimensioned to conform with the dimensions of the neck of said bag when closed;
- 25 40 45 50 55 60 65 70 75 77 80 85 90 95 100
tying means comprising a bendable, wirelike element connected to said narrow lower portion of said handle for tying around said neck to close said bag and to permit said closed bag to be carried by said handle; and annular means associated with the lower portion of said handle preventing disengagement of said tying means therefrom while mounted on said bag.
2. A combined bag closer and carrying handle as specified in claim 1, wherein:
said narrow integral lower portion of said handle is turned back upon itself to form a transverse closed loop therein; said tying means is an elongated bendable wire received in said loop and adapted to be twisted around said neck; and said closed loop constitutes said annular means preventing disengagement of said wire from said handle.
3. A combined bag closer and carrying handle, as specified in claim 1, wherein:
said narrow integral lower portion of said handle includes at least one opening; said tying means is an elongated, bendable metal wire received in said opening; and said opening constitutes said annular means preventing disengagement of said wire from said handle.
4. A combined bag closer and carrying handle as specified in claim 3, wherein:
said elongated, bendable metal wire is relatively stiff and adapted to be bent around said neck only with the mechanical advantage of a clamping tool; and said narrow lower portion of said handle is relatively limp and conformable to the bent loop of said stiff wire.
5. A combined bag closer and carrying handle comprising:

an elongated bendable wirelike element adapted to have its ends bent around the neck of a bag and twisted together into a closed loop; 5
 a handle grip, of substantially flat configuration, said grip having a wide upper portion with an aperture for receiving the fingers of a hand, and having an integral lower portion of reduced width including at least one aperture receiving and retaining the central portion of said wire against disengagement from said handle grip; and 10
 whereby when said handle is lifted, it lifts said twisted wire loop into tilted position on said neck to firmly grip said neck.
 6. In combination:
 a potato bag of paper, having its upper portion bunched together to form an upwardly projecting neck; 15
 a wire tie looped tightly around said neck and having its ends twisted together;
 a hand grip, of material other than said bag or wire tie, hav-

ing a lower portion in secured engagement with said wire tie loop for forming a handle on said bag; and
 said lower portion having at least one aperture receiving and retaining said wire tie thereon.

7. A combination as specified in claim 6, wherein said hand grip is of synthetic plastic material of predetermined stiffness, whereby the upper portion is semirigid and the lower portion attached to said tie is flexible and limp.

8. A combination as specified in claim 6, wherein said hand grip is formed of relatively flat plastic, with a wide upper portion, having a finger aperture and with said narrow lower portion looped back upon itself and forming a closed loop as the said aperture, to receive and permanently retain said wire tie.

9. A combination as specified in claim 6, wherein said lower portion of said hand grip is of enlarged thickness forming a terminal bead.
